UNITED STATES PATENT OFFICE.

FOSTER J. HERRON, OF SHERODSVILLE, OHIO.

VALVE.

1,230,161.

Specification of Letters Patent. Patented June 19, 1917.

Application filed August 11, 1916. Serial No. 114,447.

To all whom it may concern:

Be it known that I, FOSTER J. HERRON, a citizen of the United States, residing at Sherodsville, in the county of Carroll and State of Ohio, have invented certain new and useful Improvements in Valves, of which the following is a specification.

This invention has relation to valves for internal combustion engines, and the nature and objects thereof will be readily apparent to those skilled in the art to which it appertains in the light of the following explanation of the accompanying drawings, illustrating what I now believe to be the preferred embodiment or mechanical expression of my invention from among other forms and arrangements, within the spirit thereof and the scope of the appended claims.

20 However, an object of the invention is to provide a valve for internal combustion engines, said valve being of the rotary type and embodying a new and novel packing means whereby escape of pressure past the 25 port of the valve is positively precluded.

Another object of the invention is to provide a valve of the character set forth associated with and inclosed within a block or casing, whereby the same may be secured 30 to and form a part of the conventional type of motor vehicle engine after the usual tappet valves have been removed therefrom.

In addition to the foregoing, my invention comprehends improvements in the details of 35 construction and arrangement of parts to be hereinafter described and particularly set forth in the appended claims.

In the accompanying drawings in which similar and corresponding parts are designated by the same characters of reference, 40 throughout the several views in which they appear;

Figure 1, is a view in end elevation illustrating the gear casing in section, of an internal combustion engine having my improved valve applied thereto.

Fig. 2, is a horizontal sectional view taken through the upper portion of an internal combustion engine and through my improved valve and casing.

Fig. 3, is a vertical sectional view taken on the line 3—3 of Fig. 2.

Fig. 4, is a detail view in perspective illustrating a pair of packing devices in interlocking engagement, and

Fig. 5, is a view in elevation of a single one of the packing devices.

With reference to the drawings, 1 indicates the cylinder head of an internal combustion engine, 2 the crank casing thereof, and 3 the crank shaft disposed therein. In the present instance, two cylinders have been illustrated designated 4 and 5, each having a port 6 and 7, respectively extending from the interior of the cylinder to the 65 guide face 8 of the cylinder head, to which face the valve casing of the usual tappet valve construction is bolted.

The casing employed in connection with my improved form of rotary valve, is designated generally at 9, and is provided with interior recesses 10 in communication with the water jacket of the cylinder head by means of ports 11, the casing 9 is provided with a transverse opening extending entirely therethrough indicated at 12, interrupted by transverse passages 13 which intersect the openings 12 and are in alinement with the cylinder ports 6 and 7.

My improved valve is in the form of an 80 elongated cylinder 14, adapted to fit snugly within the opening 12, and to extend beyond end of the casing as at 15. The opposite end of the valve is provided with a threaded opening in which a bolt 16 is seated, the head thereof engaging a plate 17 resting against the exterior of the casing thereby providing a means to prevent removal of the valve from the casing but at the same time permitting rotary movement 90 thereof. The valve 14 is provided with valve openings 18, each arranged in the path of the opening 13 of the casing, and at relative angular relation of approximately 45°.

The end 15 of the valve is provided with 95 a sprocket 19, over which a chain 20 passes, said chain also passing over an idler sprocket 21 mounted upon a stud which projects from the engine casing. The sprocket 21 also carries a spur gear 22, which is in mesh 100 with a spur gear 23 fixed to the crank shaft of the engine. The ratio of the sprockets and gears are such as to transmit motion from the crank shaft to the valve 14 at the ratio of 1 to 4, or in other words permitting 105 four revolutions of the crank shaft to one of the valve.

I provide a novel form of packing for the rod adjacent the valve opening, and to receive the same there is provided at the oppo- 110

site longitudinal edges of the valve openings 18 at either end thereof, grooves 24. An annular groove 25 is provided circumferentially in the valve adjacent each end of 5 one of the valve openings 18, said grooves 25 being in communication with the longitudinal grooves 24. A packing device, adapted for operation in pairs, and a single one of which is illustrated in Fig. 5, com- 10 prises annular packing rings 26, each ring being offset for one half its circumference, the connecting offset portions being indicated at 27. Diametrically opposite each of said portions 27, the rings are severed as 15 at 28; the rings of a single packing device are furthermore connected in spaced relation by means of connecting bars 29 formed integrally with the rings and adjacent the offset portions 27. In assembling a pair of 20 the devices, the rings of each pair are disposed side by side, with the offset portion 27 of one ring disposed between the severed portion of the other ring. In this manner a pair of connecting bars 29 will be in op- 25 posed relation. The packing device is associated with the valve by disposing the connected rings 26 in the annular grooves 25, and the connecting bars 29 in the longitudinal grooves 24 of the valve. It will be 30 obvious that a resilient packing surface is provided entirely around each valve opening 18 of the valve. It will be further apparent that the severed portion 28 of the rings are adjacent the ends of the valve 35 openings 18. Owing to this arrangement, when the said openings are in alignment with the openings 13, no pressure to speak of exists, and consequently the presence of the severed portion does not reduce the effi- 40 ciency of the packing device. The operation of this type of valve is well known and hence further description of its operation is unessential.

While I have illustrated and described my

invention with some degree of particularity, 45 I realize that in practice various alterations thereover may be made, and I therefore re-serve the right and privilege of changing the form of the details of construction and arrangement of the correlated parts with- 50 out departing from the spirit of the invention or the scope of the appended claims.

Having thus described my invention what I claim as new and desire to secure by Let- 55 ters Patent is:

1. In an internal combustion engine, a ro- 60 tary valve in the form of a cylinder hav- ing transversely extending passages, and a packing device associated with the valve adjacent each passage comprising pairs of 65 rings adjacent the ends of the passages, each ring being offset at one portion of its circumference, the diametrically opposed point of each ring being severed, and the pairs of rings being disposed with the offset por- 70 tion of one disposed in the severed portion of the other, and bars connecting the rings of opposed pairs, said bars being disposed adjacent the longitudinal edges of the pas- sages to form a packing therefor.

2. A rotary valve having a transverse valve opening, an external annular groove formed in the surface of the valve at each end of said opening, and a groove formed longitudinally adjacent the edges of the 75 opening, and connecting the annular groove and a packing device including a pair of rings in each annular groove, and bars located in the longitudinal grooves and connecting one of the rings of one pair with one of the rings of the opposite pair.

In testimony whereof I affix my signature in presence of two witnesses.

FOSTER J. HERRON.
